UNITED STATES PATENT OFFICE.

CARL B. AUEL, OF WILKINSBURG, PENNSYLVANIA, ASSIGNOR TO WESTINGHOUSE ELECTRIC AND MANUFACTURING COMPANY, A CORPORATION OF PENNSYLVANIA.

LAMP-GUARD.

1,289,076.

Specification of Letters Patent. Patented Dec. 31, 1918.

Application filed June 4, 1915. Serial No. 32,187.

To all whom it may concern:

Be it known that I, CARL B. AUEL, a citizen of the United States, and a resident of Wilkinsburg, in the county of Allegheny and State of Pennsylvania, have invented 5 a new and useful Improvement in Lamp-Guards, of which the following is a specification.

My invention relates to guards or locking 10 devices for incandescent lamp bulbs, and it has for its object to provide a device that shall be simple and inexpensive in construction and which will be effective in preventing the unauthorized removal of incandescent 15 lamp bulbs from their sockets.

According to the present invention, I provide a lamp guard or locking device that is particularly adapted for use in connection with lamps provided with protecting shades. 20 A lamp guard constructed in accordance with my invention may be readily applied to the lamp bulb without removing the shade.

In the accompanying drawings; Figure 25 1 is a view, partially in section and partially in side elevation, of a lamp socket supporting a shade and an incandescent lamp and provided with a lamp guard constructed in accordance with my invention; Fig. 2 is a 30 plan view of the parts shown in Fig. 1; Fig. 3 is a fragmentary view in side elevation and at right angles with respect to the parts shown in Fig. 1; Fig. 4 is an elevational view of the parts shown in Fig. 1 and showing a modification of the lamp guard; Fig. 35 5 is a fragmentary view in side elevation and at right angles with respect to the parts shown in Fig. 4, and Figs. 6 and 7 are fragmentary views showing portions of the 40 lamp guard.

A lamp socket 1 of any desired form supports an incandescent lamp bulb 2 that is in threaded engagement with the socket 1 and a shade 3 that partially incloses the 45 lamp bulb 2. The shade 3 comprises a bowl shaped member 4 formed preferably of glass or any other suitable material, and a metallic ring 5 that is attached to the member 4 and is suitably supported by the socket 1. 50 The lamp guard 6 comprises a main body portion 7 that is adapted to engage the bulb 2 and a plurality of radial extensions 8. The body portion 7 comprises a pair of semi-elliptical portions 9 that are disposed 55 at an angle with respect to each other, as best shown in Fig. 3. The length of the minor axis of the substantially elliptical figure formed by the portions 9 is somewhat less than the greatest diameter of the bulb 2. The lamp guard 6 is held concentrically, 60 with respect to the bulb 2, by means of the radial extensions 8 and the shade member 4. The shade member 4 is provided with oppositely disposed aligned openings 10 which are adapted to receive the radial extensions 65 8. The radial extensions 8 are prevented from lateral movement with respect to the bulb 2 by means of a bent-over portion 11 provided at the end of one extension 8 and a locking device 12 provided at the end of 70 the other extension. The locking device 12 comprises a cup-shaped member 13 provided with a central opening to receive the end of the extension 8 and a nut 14 adapted to be in threaded engagement with the said 75 extension. The nut 14 may be turned down within the cup shaped member 13 by means of a suitable socket wrench and thereby retain the lamp guard firmly in position.

Referring now to Figs. 4 and 5, the guard 80 member 6 comprises a body portion formed of several circular turns 15 the mean diameter of which is less than the greatest diameter of the bulb 2. The guard member 6 is preferably formed of wire that may be 85 readily bent but which possesses sufficient rigidity and further comprises radial extensions 16 which are formed by continuation of the circular turns 15. The extensions 16 are inclined downwardly to clear the outer 90 periphery of the globe member 4 and are further bent to constitute upwardly extending vertical portions 17 and inclined portions 18, as best shown in Fig. 6. The inclined portions 18 severally extend up- 95 wardly and adjacent to that portion of the lamp socket 1 above the ring member 5 of the shade 3. The inclined portions 18 respectively terminate in an eye portion 19 and a semi-circular portion 20 that is 100 adapted to embrace substantially one-half of the periphery of the socket 1, as best shown in Fig. 6. The portion 20 terminates in an enlarged portion 21 that is provided with a threaded opening 22. A second 105 semi-circular portion 23 is pivotally secured to the inclined portion 18 by means of the coacting eye portions 24 and 25 and terminates in a circular lug portion 26. The lug portion 26 is provided with a hollow 110

cylindrical extension 27 and a central opening 28 adapted to be in alinement with the opening 22 of the enlarged portion 21. A bolt 29, extending through the opening 26 and the eye portion 19, is in threaded engagement with the opening 22 and serves to prevent the semi-circular portion 23 from pivotal movement with respect to the portion 18.

10 From the foregoing, it is apparent that it will be impossible to remove the lamp guard without the use of a socket wrench especially adapted to engage the nut 14 or the bolt 29. Furthermore, the lamp guard may 15 be readily applied to the incandescent lamp bulb without removing the shade and with a minimum amount of trouble.

While I have shown my invention in a simple and preferred form, it is not so 20 limited but is susceptible of various minor changes and modifications within the scope 25 of the appended claims.

I claim as my invention:

1. A guard for incandescent lamp bulbs 25 comprising substantially semi-elliptical portions joined at their ends so as to lie in different planes, the minor axis of the resultant closed loop being less than the greatest diameter of said bulb, and means for supporting 30 said guard to prevent displacement of said bulb.

2. A guard for incandescent electric lamps comprising a body portion adapted to engage and hold the end of a lamp bulb, two straight 35 supporting members extending in opposite directions from the said body portion and locking means associated with at least one of the said supporting members.

3. A guard for incandescent electric lamps 40 comprising a body portion adapted to en-

gage and hold the end of a lamp bulb, two straight supporting members extending in opposite directions from the said body portion and locking means associated with at least one of the said supporting members, the 45 said locking means comprising a nut in screw-threaded engagement with the end of the said supporting member and an annular protecting member surrounding the said nut.

4. An illuminating device comprising an 50 incandescent lamp socket, a shade carried by the said socket and provided with two oppositely disposed openings, and a lamp guard comprising a body portion adapted to encircle the end of the lamp bulb held in the 55 said socket, two straight supporting members extending in opposite directions from the said body portion and through the said 60 perforations in the said shade, and locking means associated with at least one of the said supporting members.

5. An illuminating device comprising an incandescent lamp socket, a shade carried by the said socket and provided with two oppositely disposed openings, and a lamp guard comprising a body portion adapted to encircle the end of the lamp bulb held in the said 65 socket, two straight supporting members extending in opposite directions from the said body portion and through the said perforations in the said shade, and locking means associated with at least one of the said supporting members, the said locking means comprising a nut in screw-threaded engagement with the end of the said supporting 70 member and an annular protecting member surrounding the said nut.

In testimony whereof, I have hereunto subscribed my name this 26th day of May 1915.

CARL B. AUEL.
